US0D1049478S

(12) **United States Design Patent** (10) Patent No.: **US D1,049,478 S**
(45) Date of Patent: ** Oct. 29, 2024

(54) **AEROSOL GENERATING DEVICE**

(71) Applicant: **Philip Morris Products S.A.**,
Neuchâtel (CH)

(72) Inventors: **Alexander Farrow**, Pleasant Hill, CA
(US); **Lily Yao**, Huizhou (CN)

(73) Assignee: **Philip Morris Products S.A.**,
Neuchâtel (CH)

(**) Term: **15 Years**

(21) Appl. No.: **29/918,474**

(22) Filed: **Nov. 28, 2023**

(57) **CLAIM**

The ornamental design for an aerosol generating device, as
shown and described.

DESCRIPTION

FIG. 1 is a front, top, and right side perspective view of an
aerosol generating device showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof;

FIG. 7 is a right side elevational view thereof; and,

FIG. 8 is another front, top, and right side perspective view
thereof shown in a position of use.

The shading in the design drawings are intended to show the
contours of the designs only and are not intended to show
ornamentation, coloration or surface finish.

1 Claim, 8 Drawing Sheets
